UNITED STATES PATENT OFFICE.

CATHERINE VIOLA WILBRAHAM, OF NEW YORK, N. Y.

DESIGN FOR A PUZZLE-BOX.

SPECIFICATION forming part of Design No. 34,806, dated July 16, 1901.

Application filed May 24, 1901. Serial No. 61,815. Term of patent 3½ years.

To all whom it may concern:

Be it known that I, CATHERINE VIOLA WILBRAHAM, a citizen of the United States, residing at the city of New York, borough of Manhattan, in the county and State of New York, have invented and produced a new and original Design for a Puzzle-Box, of which the following is a specification.

In the accompanying drawings, forming part of this specification, wherein like letters of reference indicate like parts, Figure 1 is a top or plan view of a puzzle-box embodying my design, and Fig. 2 is a section on the line 2 2 of Fig. 1.

The leading features of my design consist of the ornamental form and configuration of the puzzle-box.

In the drawings, A designates a rectangular receptacle, and B an elevated platform

arranged therein. The elevated platform B has an inclined way C arranged at one of its sides, extending downward to the base A' of the receptacle A, and D denotes a ledge extending upwardly from the elevated platform B adjacent to the inclined way C, and a a a denote circular apertures of different diameters arranged in the horizontal portion of the elevated platform B.

What I claim is—

The design for a puzzle-box, substantially as shown and described.

Signed at the city of New York, in the county and State of New York, this 22d day of May, 1901.

C. VIOLA WILBRAHAM.
